UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,218,264.

Specification of Letters Patent.

Patented Mar. 6, 1917.

Application filed March 17, 1915. Serial No. 14,893.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent No. 436532, to O. Mergenthaler, wherein circulating matrices are released 15 from a magazine in the order in which their characters are to appear in print and then assembled in line, the composed line transferred to the face of a mold, the mold filled with molten metal to form a slug or lino- 20 type against the matrices which produce the type characters thereon, and the matrices thereafter returned through distributing mechanism to the magazine from which they started. More particularly, it relates 25 to those machines equipped with a plurality of fonts of matrices, any selected one of which may be used at will.

In my prior Letters Patent, No. 1,136,535, dated April 20, 1915, I have illustrated a 30 machine equipped with two series of magazines, those of one series containing regular or main fonts, and those of the other series containing special or auxiliary fonts, and wherein the two series are arranged side 35 by side and are movable independently of each other, to bring different selected pairs of magazines into operative relation to the distributing and assembling devices for simultaneous use. The principle of such arrangement, as fully set forth in said application, is to permit the mixture of various 40 fonts or faces in the machine for the production of matter of many different descriptions.

45 My present invention specifically aims to simplify the construction shown in said application, and in particular to permit the manipulation of the magazines containing the auxiliary fonts in a convenient and expeditious manner. It is to be understood, 50 however, that my invention is equally applicable to machines employing a single series of magazines, and quite irrespective of whether they contain regular fonts or 55 auxiliary fonts of matrices.

In the accompanying drawings, I have shown my invention in preferred form and by way of example and as applied to a linotype machine of the class stated, but obviously it may be applied to other forms of 60 typographical machines, such as typesetters, type casters and the like, which handle type or dies instead of matrices. Generally speaking, I desire it to be understood that I do not limit myself to any specific 65 form or embodiment, except in so far as such limitations are specified in the claims:

Referring to the drawings:

Figure 1 is a side elevation of a linotype machine, having my invention applied 70 thereto;

Fig. 2 is a plan view, partly broken away, of a portion of the machine;

Fig. 2^a is a detail-view;

Fig. 3 is a side elevation showing principally the auxiliary magazines, certain parts being omitted and others broken away;

Figs. 4 and 5 are detail-views;

Fig. 6 is a view similar to Fig. 3, showing the parts in different position;

Fig. 7 is a detail-view;

Fig. 8 is a section on the line 8—8 of Fig. 6; and

Fig. 9 is a detail-view.

The matrices X of the regular fonts are 85 stored in the series of main magazines A carried by the supporting frame B, which is mounted in the machine frame so as to be movable up and down therein by the operation of the handle C to bring one or another of the magazines into operative 90 relation to the channeled raceway or assembler entrance H. The matrices are released from the operative magazine by the manipulation of the keyboard H² and pass onto 95 the belt H¹, which delivers them to the assembler (not shown) in the customary manner. Arranged at the side of the magazines A is a second series of supplemental magazines E, containing the auxiliary fonts, and 100 carried by the supporting frame F, which is movably mounted in the machine frame so as to bring one or another of its magazines into operative relation to the stationary throat J opening into the channeled raceway H, the latter being extended sufficiently 105 to coöperate with both series of magazines.

The auxiliary matrices are released from the active magazine E by a single series of escapements J¹ located in the throat J, and 110

which are actuated through suitable connections J^2 from the separate keyboard H^3 . Each of the escapements J^1 comprises as usual (see Fig. 7) a pivoted lever J^3 and two pawls J^4 , which are projected alternately thereby into the throat J in effecting the release of a matrix. The arrangement and operation of the escapements are the same as shown and described in my previous Letters 10 Patent No. 1,115,211, and therefore require no further description here. It may be stated, however, that the action of the escapements is such that they hold the lowermost matrices in the active magazine, and 15 after their actuation leave the throat J entirely clear of matrices, so that the magazines are free to be moved at any time without preparatory operations.

The regular matrices are returned to their 20 magazines A in the usual manner by the distributing mechanism D , which is extended longitudinally so as also to coöperate with the series of supplemental magazines E . In this connection, it will be noted that 25 the supplemental magazines are of the short and narrow kind illustrated in my previous application, and therefore require the use of the channeled conductor G and channel entrance G^1 (Fig. 3) to carry the matrices 30 thereto from the distributing mechanism. The conductor G is carried by a supporting frame G^2 , which is mounted at its upper end upon a transverse rod G^4 in the framework and is provided with adjusting screws G^5 35 engaging therewith, and at its lower end the frame rests upon a pair of adjusting screws G^3 upon the framework. In this way, the conductor G can be readily adjusted in the machine to secure the proper registration 40 of its grooved channels with those of the magazines. The general arrangement of the parts so far described, except as to the escapements and as hereinafter specified, is or may be substantially the same as 45 set forth in my pending application above referred to.

As previously stated, my present invention is directed principally to various improvements in connection with the supplemental 50 magazines E . I will first describe the manner in which they are supported in the machine. Referring particularly to Figs. 2, 2^a and 8, it will be noted that the supporting frame F comprises two side plates or members F^1 , which are suitably connected together and spaced apart by means of tie rods F^2 . The plates F^1 are formed in their inner faces with longitudinal grooves F^3 , wherein are slidably arranged the opposite 55 ends of pairs of transverse bars E^4 secured rigidly to the under side of each of the magazines E . By this arrangement, the magazines are separately supported in the frame 60 F and in such manner that any one may be 65 withdrawn forwardly therefrom independ-

ently of the others. In order to hold the magazines in place in the frame F , the latter is provided with a series of transverse locking bars S , one for each magazine, and each of the locking bars is formed with a 70 pair of upstanding lugs S^1 arranged to engage the forward edge of a transverse rib E^2 fixed to the under side of the corresponding magazine. To permit the removal of a magazine, its locking bar S is shifted longitudinally to the right to register its projecting studs S^1 with cuts or notches E^3 formed in the rib E^2 of the magazine. In this position of the parts (as seen in Fig. 2^a), the magazine is free to move forwardly in its 80 own plane without interference with the locking bar. It will be understood also that the parts should occupy the same relation when a magazine is replaced or substituted in the frame F . The locking bars S are 85 formed at one end with handle portions S^2 located outside the supporting frame F to facilitate their longitudinal movement, as just described, and at their opposite ends with further studs S^2 to engage the frame 90 F and limit their movement in such manner as to secure the proper registration of the studs S^1 with the notches E^3 in the magazine ribs E^2 .

The mechanism for moving the magazines 95 and locking them in position will next be described. Referring to Fig. 2, it will be seen that the side members F^1 of the frame F are engaged at their rear ends in upright grooves F^4 formed in the framework, and in their 100 outer faces the members are formed with grooves F^6 , wherein engage rollers F^5 , journaled in the framework and bearing upon the rear edges of the grooves, there being two such rollers in each groove, see Fig. 8. 105 In this way, the frame F is held against both forward or lateral displacement and is accurately guided in its up and down movements. As shown in Figs. 1, 3 and 8, the side members F^1 are also provided with 110 downwardly projecting arms F^7 , which are connected by a transverse rod F^8 . This rod passes through an elongated slot K^2 formed in a long hand lever K , which is pivoted at its rear end, as at K^1 , to the machine frame, 115 and has its front end offset, as at K^3 (see Fig. 2) so as to stand between the two series of magazines and thus be capable of free vertical movement. By raising and lowering the hand lever K , therefore, the frame 120 F is correspondingly raised and lowered to bring the selected magazine into operative position. To facilitate the movement of the magazines, there is provided a counterbalancing spring T (see Figs. 1 and 3), connected at one end to the frame G^2 and at its 125 opposite end directly to the lever K in advance of its pivotal point.

The frame F is held in its shifted position by a pair of longitudinally movable 130

locking bars L slidably mounted in guideways L⁵ of the framework and having at opposite ends lateral projections L¹, which are adapted to engage in one or another of 5 a plurality of notches F¹⁰ formed in plates F⁹ carried by the frame F, there being two such plates F⁹ applied to the outer face of each of the two side members F¹ and each having as many notches F¹⁰ as there are 10 magazines in the frame (see in particular Fig. 2). The locking bars L are normally held with their projections L¹ in engagement with the notches F¹⁰ by springs L³ connected at one end to the bars and at the 15 opposite end to the framework. As shown in Figs. 1, 2 and 3, a pair of arms or levers M, fixed to the opposite ends of a transverse rock shaft M¹, have their free ends arranged behind and in engagement with 20 small rollers L⁴ secured to the forward ends of the bars L. By rocking the two arms M forwardly, therefore, the bars L are moved therewith and their locking projections L¹ are thus disengaged from the notches F¹⁰. 25 The forward movement of the levers M is effected by means of a sliding plate K⁴ connected by pin-and-slot connections to the hand lever K and having a laterally projecting roller K⁷ arranged to bear upon 30 a curved surface M² formed on one of the arms M, (see Figs. 2, 3 and 4). The plate K⁴ is connected by a link K⁵ to an operating member K⁶ pivoted to the hand lever K at its grip portion. The effect of the arrangement 35 is that when the hand lever K is grasped by the operator for the purpose of moving the magazines, the plate K⁴ is drawn forwardly so as to rock the arms M and disengage the locking bars L from the 40 movable supporting frame F. It is pointed out that the curvature of the surface M² is such that when the lever M is in its forward position, the curvature coincides with the arc of a circle described from the pivotal 45 point K¹ of the lever K as a center, the purpose being to avoid any interference with the levers M and the connected locking bars L, as the hand lever K is raised and lowered to move the magazines. 50 In order to prevent the unlocking of the auxiliary magazines E when matrices are still in course of distribution, I propose to connect the locking bars L with the well-known matrix feeler or detector R, as follows:—Referring to Figs. 1, 3 and 5, the feeler R is mounted so as to be swung transversely into and out of the distributing mechanism by an arm R¹, which is connected to the upper end of a lever R², pivoted 55 between its ends to the framework, as at r³, and provided at its lower end with a curved portion R⁴. Coöoperating with the portion R⁴ is a roller R⁵ (see Fig. 5) carried upon the rear end of a link R⁶ slidably engaged 60 in a grooved block R⁷ of the framework and

connected at its forward end, as at R⁸, to the sliding plate K⁴ attached to the hand lever K. As a result of this arrangement, when the plate K⁴ is drawn forwardly to move the locking bars L to inactive position, the feeler R is projected into the path of the matrices passing through the distributing mechanism. Consequently, if any matrices are present therein, the movement of the feeler R is arrested thereby and the 70 forward movement of the plate K⁴ is thus prevented, so that the unlocking of the magazines cannot take place. If, on the other hand, no matrices are in course of distribution, the feeler R is not so arrested, 75 and the plate K⁴ is then free to be drawn forwardly to unlock the magazines. It is pointed out that the curvature of the portion R⁴ of the lever R² is such that when the latter is in its operated position, the curvature will stand concentric with the path of movement of the roller R⁵ of the link R⁶, so that the latter may be moved freely with the hand lever K, to which it is connected, 80 without any tendency to move the lever R². 85 It should also be noted that the block R⁷ is pivotally mounted in the machine frame to permit the movement of the link R⁶ in the manner just stated, (see Fig. 2). 90

Since the magazines E are without escapements, means are provided to hold the matrices therein when they are out of operative position or when they are removed from the machine. To this end, each magazine is provided with a transverse locking device O, of well known construction, which is rotatably mounted in bearings on the upper side thereof so as to be movable into and out of the magazine and thus be engaged with and disengaged from the upper ears of the lowermost matrices therein, (see Figs. 2 and 7). Each of the locking devices O is provided at one end with an arm O¹ (see Figs. 3 and 6) which is connected to a spring O² fastened to the magazine and tending to hold the locking device in its active position. To move the locking devices to inactive position, against the force of their springs, each of the magazines is provided at its side edge with a sliding plate O⁴, connected thereto by pin-and-slot connections, and having at its forward end an inclined surface O⁵ arranged to engage a roller O² projecting inwardly from the arm O¹. (see also Fig. 2). 105

The plates O⁴ are in turn movable by a series of blocks P arranged to slide back and forth in elongated slots P² formed in one of the side members F¹ of the frame F, there being as many such blocks P as there 110 are magazines in the machine. As shown clearly in Fig. 9, the blocks P are formed with flanges P³ which embrace the frame member F¹ on opposite sides of the slots P², and thus guide the blocks accurately in 115 120 125 130

their sliding movements. The blocks are also formed on their opposite edges with laterally projecting studs P^1 , the inner ones being arranged to engage lateral projections O^6 on the sliding plates O^4 , while the outer ones are adapted to be engaged by the upper end of a lever N pivoted at N^1 to the framework and having its lower end in position to be engaged by a roller L^2 on one 5 of the locking bars L . (see particularly Fig. 8). A spring N^2 connected at one end to the framework and at its opposite end to the lever N serves to hold its upper end out of engagement with the studs P^1 of the blocks P and with its lower end in engagement with the roller L^2 . It will be understood that the lever N is arranged to act upon only one of the blocks P at a time, namely, the one which is associated with 10 the magazine in action.

The operation of these parts will now be clear. When one of the magazines is in operative position, its locking device O is held in inactive condition by the plate O^4 15 which has been moved forwardly through the medium of the block P by the pivoted lever N , the latter being so arranged that the locking bar L , when in active position, holds it in its forward position as shown in 20 Fig. 6, it being noted that the spring L^3 of the locking bar L is of sufficient strength to overcome the resistance of the two springs N^2 and O^3 connected to the pivoted lever N and locking device O respectively. When, 25 however, the locking bar L is moved forwardly to unlock the magazines, its roller L^2 is disengaged from the lever N , which is then pulled rearward by its spring N^2 (as shown in Fig. 3), this action of the parts 30 also allowing the spring O^3 to move the locking device O of the magazine to active position and also to restore the plate O^4 and member P to their original positions. The magazines are now free to be shifted, the 35 matrices being securely locked in all of them. When another magazine is now brought into operative position, the above action is reversed, namely, the locking bar L is moved rearwardly by its spring L^3 to engage the 40 projections L^1 in the notches F^{10} of the magazine frame F , which movement of the bar causes the roller L^2 to engage the lower end of the lever N and shift its upper end forwardly against the action of the spring 45 N^2 . This movement of the lever N through the medium of the member P slides the plate O^4 on the magazine forwardly, the inclined surface O^6 of the plate engaging the roller O^2 on the arm O^1 of the locking 50 device O and rotating it to inactive position against the action of its spring O^3 . The matrices in the operative magazine are now 55 free to be released therefrom by the escape- 60 ments J^1 , as before described. Briefly stated, 65 the effect of this arrangement is that when

the magazines E are unlocked for movement, the matrices in the active magazine are simultaneously locked therein; and conversely, when the magazines are re-locked in their moved position, the matrices are 70 unlocked in the new magazine. It will also be seen the arrangement of the parts is such that the connections between the locking devices O and their actuating means will not interfere with the removal of the magazines from their supporting frame, and also that when the magazines are so removed from the machine, there will be no danger of the matrices escaping therefrom, it being noted that the locking devices O are held 80 normally in their active position due to the action of the springs O^3 .

The general operation of the parts will have been understood from the foregoing description. It may be noted, however, that 85 the matrix locking devices O , the magazine locking devices L , and the matrix feeler R , are all operated simultaneously before and after the shifting of the magazines, the construction being such that the matrix locking devices are moved to active and inactive 90 position as the magazine locking devices are moved to inactive and active position, respectively, and also that the operation of such locking devices is allowed or prevented 95 according to whether matrices are absent from or present in the distributing mechanism.

While in the accompanying drawings I have shown my invention as applied to the 100 special form of magazines described, it will be obvious that it is equally applicable to magazines of ordinary construction, quite irrespective of whether they are used as auxiliary magazines or main magazines. It 105 will also be understood that my invention has been shown merely in preferred form and by way of example, and that many changes and variations therein and in its mode of application will readily suggest 110 themselves to those skilled in the art without departure from its scope.

Having thus described my invention, its construction and mode of operation, what I claim and desire to secure by Letters Patent 115 of the United States, is, as follows:

1. In a typographical machine, the combination of a plurality of magazines, a supporting frame therefor movable to bring one or another of the magazines into operative 120 position, and comprising two connected side members having projecting end portions, and the machine frame in which the supporting frame is mounted, the said machine frame being formed with grooves wherein 125 the projecting end portions of the side members of the supporting frame slidably engage.

2. In a typographical machine, the combination of a plurality of magazines, a sup- 130

porting frame therefor movable to bring one or another of the magazines into operative position, and comprising two connected side members, and the machine frame in which the supporting frame is mounted, the said machine frame being formed with grooves wherein the rear ends of the side members of the supporting frame slidably engage, and also provided with guiding rollers bearing against the side members of the supporting frame to prevent its forward displacement.

3. In a typographical machine, the combination of the machine frame formed with the grooves F^4 and provided with the rollers F^5 , and the movable magazine supporting frame F comprising the side members F^1 , the said members engaging at their rear ends in the grooves F^4 and being provided 20 in their outer faces with the grooves F^6 wherein the rollers F^5 engage.

4. In a typographical machine, the combination of a plurality of magazines, a supporting frame therefor, and means for moving the supporting frame to bring one or another of the magazines into operative position, the said means including a hand lever pivoted to the machine frame and connected between its ends directly to the movable supporting frame by a pin-and-slot connection.

5. In a typographical machine, the combination of the movable magazine supporting frame F comprising the side members F^1 having the depending arms F^7 which are connected by the transverse rod F^8 , and the hand lever K for moving the supporting frame, the said lever being pivoted at its rear end to the machine frame and formed 40 with the elongated slot K^2 wherein the rod F^8 engages.

6. In a typographical machine, the combination of a supporting frame, a magazine adapted to slide forwardly thereon and provided on one face with a transverse rib formed with a notch or recess, and a transverse bar provided with a projecting stud to engage the rib and hold the magazine in place on the supporting frame, the said bar being movable to register its stud with the notch in the rib to permit the magazine to slide forwardly.

7. In a typographical machine, the combination of a supporting frame, a magazine adapted to slide forwardly thereon, and provided on one face with a transverse rib formed with notches or recesses at its opposite ends, and a transverse bar provided with projecting studs to engage the forward edge 60 of the rib at one side of its notches and hold the magazine in place on the supporting frame, the said bar being movable longitudinally to register its studs with the notches in the rib to permit the magazine to slide 85 forwardly.

8. In a typographical machine, the combination of a supporting frame, a magazine adapted to slide forwardly thereon and provided on one face with a transverse rib formed with a notch or recess, and a transverse bar provided with a projecting stud to engage the rib and hold the magazine in place on the supporting frame, the said bar being movable to register its stud with the notch in the rib to permit the magazine to slide forwardly, and being formed with a further stud to engage the supporting frame and limit its movement so as to insure the registration of the first-mentioned stud with the notch in the magazine rib.

9. In a typographical machine, the combination of a plurality of magazines, a supporting frame therefor movable to bring one or another of the magazines into operative position, the said magazines being mounted in the supporting frame so as to slide forwardly for removal, and each provided with a transverse rib on its under side, and a series of transverse bars carried by the supporting frame and formed with upstanding projections to engage the ribs on the under side of the magazines and hold them in place, the said bars being movable longitudinally independently to disengage their projecting studs from the corresponding ribs, and thus to permit the independent removal of one or another of the magazines.

10. In a typographical machine, the combination of a plurality of magazines, a supporting frame therefor movable to bring one or another into operative position and comprising two connected side members, the said magazines being mounted in the supporting frame so as to slide forwardly therein for removal, and each provided on its under side with a transverse rib, and a plurality of bars carried by the supporting frame and provided with projecting studs to engage the transverse ribs of the magazines and hold them in place in the frame, and movable longitudinally to disengage said studs from the ribs to permit the forward removal of the magazines, the said bars being provided at one end with operating handles which are located outside of the supporting frame to permit their convenient operation.

11. In a typographical machine, the combination of a plurality of magazines, a supporting frame therefor movable to bring one or another into operative position, means for effecting the movement of the supporting frame including a hand lever movable upwardly and downwardly about a transverse pivot, a longitudinally movable locking bar to hold the supporting frame in its moved position, and means carried by the hand lever for operating the locking bar.

12. In a typographical machine, the combination of a plurality of magazines, a sup-

- porting frame therefor movable to bring one or another into operative position, means for effecting the movement of the supporting frame including a hand lever movable upwardly and downwardly about a transverse pivot, a longitudinally movable locking bar to hold the supporting frame in its moved position, an operating member carried by the hand lever, and connections from the operating member to the locking bar, said connections including an arm pivoted at one end to the machine frame and connected at its other end to the bar.
13. In a typographical machine, the combination of a plurality of magazines, a supporting frame therefor movable to bring one or another into operative position, means for effecting the movement of the supporting frame including a pivoted hand lever, a longitudinally movable locking bar to hold the supporting frame in its moved position, an operating member carried by the hand lever, and connections from the operating member to the locking bar, said connections including an arm pivoted at one end to the machine frame and connected at its other end to the bar, and a plate slidably mounted on the hand lever and connected to the pivoted arm and the operating member, respectively.
14. In a typographical machine, the combination of a plurality of magazines, a supporting frame therefor movable to bring one or another into operative position, means for effecting the movement of the supporting frame including a pivoted hand lever, a longitudinally movable locking bar to hold the supporting frame in its moved position, and an operating member carried by the hand lever, and connections from the operating member to the locking bar, said connections including an arm pivoted at one end to the machine frame and connected at its other end to the bar and formed with a curved face, and a sliding plate carried by the hand lever and connected to the operating member and provided with a laterally projecting roller bearing upon the curved face of the pivoted arm, for the purpose described.
15. In a typographical machine, the combination of a plurality of magazines, a supporting frame therefor movable to bring one or another into operative position, a pivoted hand lever for effecting the movement of the supporting frame, a longitudinally movable bar for holding the frame in its moved position, an upright arm pivoted to the machine frame for moving the locking bar longitudinally, and means connected to the upright arm for rocking it to move the locking bar, the said means being carried by the hand lever and movable therewith without becoming disconnected from the pivoted arm.
16. In a typographical machine, the combination of a plurality of magazines, a supporting frame therefor movable to bring one or another into operative position, means for effecting such movement of the supporting frame including a hand lever movable upwardly and downwardly about a transverse pivot, a feeler or detector to cooperate with the matrices in course of distribution, and means carried by the hand lever for controlling the operation of the matrix feeler.
17. In a typographical machine, the combination of a plurality of magazines, a supporting frame therefor movable to bring one or another into operative position, means for effecting such movement of the supporting frame including a hand lever movable upwardly and downwardly about a transverse pivot, a locking device to hold the frame in its moved position, a feeler or detector to cooperate with the matrices in course of distribution, an operating member carried by the hand lever, and connections between said member and the matrix feeler.
18. In a typographical machine, the combination of a plurality of magazines, a supporting frame therefor movable to bring one or another into operative position, means for effecting such movement of the supporting frame including a pivoted hand lever, a locking device to hold the frame in its moved position, a feeler or detector to cooperate with the matrices in course of distribution, an operating member carried by the hand lever, and connections between said member and the matrix feeler, said connections including a longitudinally extending link, and a pivoted lever connected at its upper end to the matrix feeler and at its lower end to the link.
19. In a typographical machine, the combination of a plurality of magazines, a supporting frame therefor movable to bring one or another into operative position, means for effecting such movement of the supporting frame including a pivoted hand lever, a feeler or detector to cooperate with the matrices in course of distribution, an operating member carried by the hand lever, and connections between said member and the matrix feeler, said connections including a longitudinally extending link provided at its rear end with a roller, and a pivoted lever connected at its upper end to the matrix feeler and formed at its lower end with a curved portion upon which the roller bears, for the purpose described.
20. In a typographical machine, the combination of a plurality of magazines, a supporting frame therefor movable to bring one or another into operative position, means for effecting such movement of the supporting frame including a hand lever movable upwardly and downwardly about a transverse pivot, a feeler or detector to cooperate with the matrices in course of distribution, an operating member carried by the hand lever, and connections between said member and the matrix feeler.

and the matrix feeler, said connections being such as to permit the free and unimpeded pivotal movement of the hand lever.

21. In a typographical machine, the combination of a plurality of magazines, a supporting frame therefor movable to bring one or another into operative position, means for effecting such movement of the supporting frame including a pivoted hand lever, a 10 feeler or detector to coöperate with the matrices in course of distribution, an operating member carried by the hand lever, connections between said member and the matrix feeler, including the longitudinally extending link R⁶, and the guide block R⁷ in which the link is slidably arranged, the said block being pivotally mounted in the machine frame, for the purpose described.

22. In a typographical machine, the combination of a plurality of magazines, a supporting frame therefor movable to bring one or another into operative position, means for effecting such movement of the supporting frame, including a hand lever movable upwardly and downwardly about a transverse pivot, a longitudinally movable locking bar to hold the supporting frame in its moved position, a feeler or detector to coöperate with matrices in course of distribution, and 20 common operating means for the locking bar and matrix feeler carried by the pivoted hand lever.

23. In a typographical machine, the combination of a plurality of magazines, a supporting frame therefor movable to bring one or another into operative position, means for effecting such movement of the supporting frame including an operating hand lever, a longitudinally movable locking bar to hold 30 the supporting frame in its moved position, a feeler or detector to coöperate with matrices in course of distribution, an operating member carried by the hand lever, and separate connections between said operating member and the locking bar and matrix feeler, respectively.

24. In a typographical machine, the combination of a plurality of magazines, a supporting frame therefor movable to bring one or another into operative position, a longitudinally movable locking bar to hold the supporting frame in its moved position, operating means for said locking bar, a feeler or detector to coöperate with matrices in 50 course of distribution, and connections independent of the locking bar between the matrix feeler and the operating means for the locking bar.

25. In a typographical machine, the combination of a plurality of magazines, a supporting frame therefor movable to bring one or another into operative position, means for effecting such movement of the supporting frame including a pivoted hand lever, a 60 longitudinally movable locking bar to hold

the supporting frame in its moved position, a feeler or detector to coöperate with the matrices in course of distribution, and common means for operating the locking bar and matrix feeler, the said means comprising an operating member carried by the hand lever, a sliding plate also carried by the lever and connected to the operating member, and separate connections between the sliding plate and the locking bar and 70 matrix feeler, respectively.

26. In a typographical machine, the combination of a plurality of magazines, each provided with a locking device for the type or matrices, a supporting frame wherein the magazines are removably mounted, means for moving the supporting frame to bring one or another of the magazines into operation, and automatic means carried by the respective magazines for holding their locking devices in active position when they are out of operation; whereby the magazines may be removed from the supporting frame without affecting the position of the locking devices.

27. In a typographical machine, the combination of a plurality of magazines each provided with a locking device for the type or matrices, a supporting frame wherein the magazines are removably mounted, means for moving the supporting frame to bring one or another of the magazines into operation, and springs carried by the respective magazines for holding their locking devices in active position when they are out of operation and during their removal; whereby the removal of the magazines from the supporting frame will not interfere with the position of the locking devices.

28. In a typographical machine, the combination of a plurality of magazines each provided with a locking device and a spring for holding it normally in active position, said magazines being movable transversely to bring one or another into operation, and means for moving the locking device of the operative magazine to inactive position to permit the delivery of type or matrices therefrom.

29. In a typographical machine, the combination of a plurality of magazines, each provided with a locking device for the type or matrices and a spring to hold it normally in active position, means for moving the magazines to bring one or another into operation, a movable locking device to hold the magazines in their moved position, and connections whereby the movement of the magazine locking device to active position effects the movement of the matrix locking device of the operative magazine to inactive position against the action of its spring.

30. In a typographical machine, the combination of a plurality of magazines each provided with a locking device for the type

or matrices and also a sliding plate for actuating the locking device, means for moving the magazines to bring one or another into operation, and means for effecting the sliding movement of the plate on the operative magazine to actuate its locking device.

31. In a typographical machine, the combination of a plurality of magazines each provided with a locking device for the type or matrices and also a sliding plate for actuating the locking device, a supporting frame for the magazines movable to bring one or another into operative position, a locking bar to hold the supporting frame in its different operative positions, and means controlled by the locking bar for effecting the sliding movement of the plate on the operative magazine to actuate its locking device.

32. In a typographical machine, the combination of a plurality of magazines each provided with a locking device for the type or matrices and also a sliding plate to actuate the locking device, a supporting frame wherein the magazines are mounted and provided with a series of sliding blocks to engage and operate the sliding plates thereon, means for moving the supporting frame to bring one or another of the magazines into operation, and means for actuating the locking device of the operative magazine through the medium of its sliding plate and the corresponding sliding block on the supporting frame.

33. In a typographical machine, the combination of a plurality of magazines each provided with a locking device for the type or matrices and also a sliding plate to actuate the locking device, a supporting frame wherein the magazines are mounted and provided with a series of sliding blocks to engage and operate the sliding plates thereon, means for moving the supporting frame to bring one or another of the magazines into operation, and a lever pivoted in the machine frame and arranged to engage and move the sliding block corresponding to the operative magazine to actuate its locking device.

34. In a typographical machine, the combination of a plurality of magazines each provided with a locking device for the type or matrices and also a sliding plate to actuate the locking device, a supporting frame wherein the magazines are mounted and provided with a series of sliding blocks to engage and operate the sliding plates thereon, means for moving the supporting frame to bring one or another of the magazines into operation, a locking device to hold the magazines in their moved position, and a pivoted lever controlled by the magazine locking device and arranged to engage and operate the sliding block associated with the magazine in operation.

35. A magazine for typographical ma-

chines provided with a rotatable locking device for the type or matrices and also a sliding plate to rotate the locking device, the said locking device provided at one end with an arm carrying a roller, and the sliding plate formed with an inclined surface to engage the roller.

36. A magazine for typographical machines provided with a rotatable locking device, a spring to hold it normally in active position, and a sliding plate to rotate it to inactive position against the action of the spring.

37. In a typographical machine, the combination of a magazine provided with a movable locking device for the type or matrices, a supporting frame for the magazine, and means for moving its locking device to inactive position, said means including a sliding plate attached to the magazine and a sliding block carried by the supporting frame and arranged to engage said plate.

38. In a typographical machine, the combination of a magazine provided with a movable locking device for the type or matrices, a supporting frame wherein the magazine is removably mounted, and means for moving said locking device to inactive position, said means including a sliding plate attached to the magazine and a sliding block carried by the supporting frame, and the said plate and block being arranged so as to be disengaged by the removal of the magazine.

39. In a typographical machine, the combination of a magazine provided with a movable locking device for the type or matrices, a supporting frame for the magazine, and means for moving its locking device to inactive position, said means including a sliding plate attached to the magazine and provided with a laterally projecting lug, and a sliding block carried by the supporting frame and provided with a laterally projecting stud adapted to engage the lug of the sliding plate.

40. In a typographical machine, the combination of a magazine provided with a movable locking device for the type or matrices, a supporting frame for the magazine, and means for moving its locking device to inactive position, said means comprising a sliding plate carried by the magazine and provided with a laterally projecting lug, a sliding block carried by the supporting frame and provided with oppositely projecting studs, one of which engages the lug of the sliding plate, and a pivoted lever arranged to engage the other stud of the block.

41. In a typographical machine, the combination of a plurality of magazines each provided with a matrix locking device and a spring for holding it normally in locking position, means for moving the magazines

to bring any selected one thereof into operation, and automatic means for shifting its matrix locking device to unlocking position when the selected magazine is brought 5 into operation.

42. In a typographical machine, the combination of a plurality of magazines each provided with a matrix locking device and a spring for holding it normally in locking 10 position, means for moving the magazines to bring any selected one thereof into operation, and automatic means for shifting its matrix locking device to unlocking position when the selected magazine is brought into

operation, the said means including a movable operating member mounted independently of the magazines and common to all the matrix locking devices thereof, and adapted to be connected to the locking device of the selected magazine when the latter is brought into operative position. 15

In testimony whereof, I have affixed my signature in presence of two witnesses.

DAVID S. KENNEDY.
